UNITED STATES PATENT OFFICE.

JOSEPH LYNAM, OF SAN JOSÉ, CALIFORNIA.

GLOBE.

SPECIFICATION forming part of Letters Patent No. 444,796, dated January 13, 1891.

Application filed March 7, 1890. Serial No. 342,974. (No model.)

To all whom it may concern:

Be it known that I, JOSEPH LYNAM, a citizen of the United States, residing in the city of San José, county of Santa Clara, and State 5 of California, have invented certain new and useful Improvements in Globes, of which the following is a specification.

My invention relates to the production of a globe of the terrestrial or the celestial sphere 10 and a support or stand in parts to be taken apart and packed in small compass for transportation or storing and capable of being readily put together and set up for use without any special skill.

15 The invention includes a globe of the terrestrial or the celestial sphere made in separate pieces or sections and novel means of fastening and holding these sections together; also, improved device for suspending or for 20 supporting it on a center for rotation; also, an improved construction of magnetic pole.

The nature of these improvements and the manner in which I proceed to construct, produce, and carry out the same will be understood 25 from the following description and the accompanying drawings, that form part thereof, and is referred to therein by figures and letters.

Figure 1 represents a globe constructed according to this invention and the device for suspending it. Fig. 2 shows the same globe mounted on the supporting-stand. Fig. 3 is a vertical section through the globe and the fastening devices on a larger scale. Fig. 4 is 35 a horizontal section through one of the separate pieces or sections of which the globe is formed. Fig. 5 is a movable scale or measure for degrees of longitude. Fig. 6 is an enlarged transverse section of the magnetic pole.

40 This globe is made in separate pieces or sections of equal size, which may be quarters for a small globe and smaller sections for a globe of larger diameter, and the parts joining one to the other on lines of longitude from 45 pole to pole are finished on the edges to make close joints.

The surface of the globe has the continents, islands, and other land portions in relief, with the contour of the surface properly shaped to 50 represent all the natural elevations and depressions of surface, the globe-sections being

produced either by dies or molds or by building up by hand from any suitable substance or material in similar manner to the production of relief-maps. Paper or paper-pulp, or 55 papier-maché, or other material that can be struck up or pressed in dies, or any material or substance that can be run in the molds or pressed into shape, can be used to make these globe-sections.

60 On the edges of each globe-section are flanges that set inward toward the center, the faces of which are grooved or finished smoothly to produce close joints along the meeting edges. These flanges are increased in depth from the 65 poles toward the equator to strengthen the section at the center. A shoulder or rim is formed on the end of the sections that fits closely around a bolt having a clamp-nut on the outer threaded end. These shoulders 70 form a neck to take a washer, and the bottom face of the nut, setting against the washer, acts to draw and hold the sections tightly together, the outer face of the neck being finished with a taper and the inner edge 75 of the washer being beveled to fit the neck. When the nut is screwed down, the washer is crowded against the neck and the sections are clamped between the head of the bolt beneath and the nut above. The heads of the 80 nuts are turned down to fit bearings on the end of a semicircular bail and form trunnions on which the globe is free to revolve. The bail furnishes both a support for the globe when mounted on its stand and carries 85 it when it is suspended. This bail or "semi-meridian," as it may be termed, being a part of the globe mountings, has a post or center pin to fit a socket in the stand, and also a 90 ring or loop for attaching the end of a suspending-cord, which is set up against the base by a top bolt.

95 The stand for the globe is constructed in parts to be separated for packing, and is composed of a base-block with a socket for the center post, removable legs, and a clamping device to hold the leg in place when set up. The base is slotted to let in the legs, and the ends of the legs that set into the base are grooved on the under side to take over the 100 rim of a cup-shaped washer or clamping-piece. The socket has a step in the bottom for the

end of the center post and a bearing at the top. The magnetic pole is fixed in the end of the bolt that forms a part of the clamping-device, and it is of novel construction in being composed of a central rod or core of soft iron and a number of magnetized wires or rods surrounding the core. This construction is intended to furnish a magnetic pole of considerable power and to reduce the size of the pole, at the same time making it sufficiently sensitive to turn the globe readily. The construction of these parts will be readily understood from the drawings, where A A indicate the globe sections, A' the line of joints, and A² the flanges on the edges.

A³ A³ are the shoulders on the ends of the globe-section, and B B the bolts that form part of the clamping devices at the poles. The head B^x of the bolt is shaped to conform to the curvature of the sections against which it fits, and the body is screw-threaded for the nut D. The bottom face of the nut is recessed to take over the neck formed by the meeting ends of the globe-sections, and its rim is milled.

C is the washer that is placed over the neck under the nut, its inner edge being beveled to fit the neck.

D^x D^x are the trunnions on the heads of the nuts, and E E are the bearings formed on the ends of the bail F. The bail extends from pole to pole and serves to support the globe upon the stand or to suspend it in space by means of a cord and pulleys. The first-named position is shown in Fig. 2 of the drawings, while the other position is shown in Fig. 1.

G is a center post fixed on the bail by a tubular collar or sleeve G^x, that forms the head of the post, and a clamp-screw G², and H is a loop or similar sleeve with a clamp-screw h^x for fixing it on the bail and an eye h² for securing to it the end of the suspending-cord X.

I is the base of the stand, with slots I' for the legs, and K are the legs, with grooved ends K^x fitted over the standing rim L^x of the cup-shaped clamp-plate L.

M is the screw or bolt, that is tapped into the bottom of the base.

The construction shown in Fig. 2 has three legs, and the clamping-piece L fits into the recess in the bottom of the base.

Figs. 3 and 6 illustrate the construction of the magnetic pole, P being the core or central rod of soft iron, and P* the rod-magnets surrounding it. The rod P is formed with a guard-plate p² and a screw end p³ on the bottom, that is tapped into a threaded socket p⁴ in the end of the bolt D. The rods or wires p^x are set closely around the center rod, and the conical head P', fixed over the ends, forms a single point to the pole. The clustered magnets are fastened at the lower ends to the collar

and are confined at the upper ends by the 65 conical cap.

The flexible scale S (see Fig. 5) is a tape with the degrees and divisions marked on it and having one end attached to a ring S^x, which is fitted on the nut D below the milled 70 edge and rests on the washer to turn loosely, the tape being left free to hang down and be shifted over the globe from one point to another.

In forming the globe-sections care should 75 be taken to have the joints between one section and another fall on the lines of longitude, and by finishing the edges of the sections to give close joints the dividing-lines will be practically invisible and the globe will appear as though made in one piece.

As thus constructed and produced, it will be seen that the globe and its mounting, when taken apart for shipment, can be packed in very small compass; also that it is readily 85 set up by a person of ordinary intelligence.

Having thus fully described my invention, what I claim, and desire to secure by Letters Patent, is—

1. A knockdown globe formed of sections 90 joined together on lines of longitude, said sections being provided with shoulders at the pole ends and flanged meeting edges along the longitudinal divisions, in combination with a clamp or binding device set over said shoulders to hold the sections together, as set forth.

2. A knockdown globe formed of sections which join together on lines of longitude, said sections having relief-surfaces, in combination with butt-joints with internal flanges 100 and shouldered ends at the poles, and clamping devices by which the sections are bound together at the poles, substantially as described.

3. The combination of the separable globe-sections having shoulders or projections on the ends, bolts having broad heads fitting the inside of the globe, and threaded stems which project through the ends, and nuts having clamping-flanges on their under faces to confine the shoulders, and trunnions on their upper faces, and a bail having bearings in which the trunnions operate, as set forth.

4. The combination of a sectional globe having shouldered ends, a bolt extending up 115 between said ends and provided with a threaded opening in its outer end, a nut screwed upon the bolt and having a flange confining the shoulders of the sections, and a pole-magnet having a screw for engagement 120 in the threaded opening in the end of the bolt, as set forth.

In testimony that I claim the foregoing I have hereunto set my hand and seal.
